CLAIM

The ornamental design for a doll, as shown and described.

DESCRIPTION

FIG. 1 is a perspective view of a doll showing my new design;

FIG. 2 illustrates a front view thereof;

FIG. 3 illustrates a back view thereof;

FIG. 4 is a side view as seen from the right side of FIG. 2;

FIG. 5 is a side view as seen from the left side of FIG. 2;

FIG. 6 is a bottom view thereof; and,

FIG. 7 is a top view thereof.

The legs and feet are shown in different positions in the various views.
